Primary Examiner — T Chase Nelson*Assistant Examiner* — Kelly L Gross(74) *Attorney, Agent, or Firm* — Seed Intellectual Property Law Group LLP**(57) CLAIM**

The ornamental design for a medical examination probe, as shown and described.

DESCRIPTION

FIG. 1 is a top, front, right side perspective view of a medical examination probe showing our new design.

FIG. 2 is a top, rear, right side perspective view thereof.

FIG. 3 is a top plan view thereof.

FIG. 4 is a bottom plan view thereof.

FIG. 5 is a right side elevation view thereof.

FIG. 6 is a left side elevation view thereof.

FIG. 7 is a rear elevation view thereof; and,

FIG. 8 is a front elevation view thereof.

The broken lines in the figures are for the purpose of illustrating aspects of the medical examination probe that form no part of the claimed design.
